Primary Examiner — Kevin Rudzinski(74) *Attorney, Agent, or Firm* — Fenwick & West LLP**CLAIM**

We claim the ornamental design for a display panel of a programmed computer system with a graphical user interface, as shown and described.

DESCRIPTION

The FIGURE is a front view of a display panel of a programmed computer system with a graphical user interface. The broken lines shown in the drawings illustrate portions of the graphical user interface that form no part of the claimed design.
